(57) **CLAIM**

The ornamental design for a sleeve for a RV drain tube, as shown and described.

DESCRIPTION

FIG. 1 is a front perspective view of a sleeve for a RV drain tube, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an exploded front perspective view thereof.

The evenly dashed broken lines shown in FIG. 8 illustrate portions of the sleeve for a RV drain tube that form no part of the claim.

The trademark material containing the logo HOTPOOPIPE! forms part of the claimed design and is owned by the inventor.
